VISCOSIMETER

James Norman Goodier, Toronto, Ontario, Canada, assignor to Ontario Research Foundation, Toronto, Ontario, Canada

Application May 25, 1936, Serial No. 81,638

9 Claims. (Cl. 265—11)

This invention relates to viscosimeters of the type in which samples of a liquid whose viscosity is to be tested are introduced into a narrow space between two relatively movable surfaces, 5 the resistance to rotation under similar conditions serving as a measure of the viscosity of any given film, and my object is to provide apparatus of this type which will enable an operator to quickly test successive samples of liquid at a standard temperature without requiring the taking of exactly measured samples.

I attain my object by means of a construction which may be briefly described as follows:

The basis of the device comprises an imperforate bowl shaped member and a second imperforate member concentric with and normally positioned within the bowl with its external surface slightly spaced from the internal surface of the latter to form a space to contain a thin 15 film of the liquid to be tested. While the width of this space may vary I find fifteen one-thousandths of an inch is satisfactory for one type of patent leather varnish.

The two members are relatively rotatable and 20 for convenience may be referred to as the stator and rotor. The bowl will ordinarily be the stator and the other member the rotor. The rotor and stator are movable axially relative to one another to facilitate the introduction of liquid into the stator. The stator is water-jacketed for cooling purposes.

The invention is hereinafter more specifically 25 described and is illustrated in the accompanying drawing in which

30 Fig. 1 is a vertical section of the device; and Fig. 2 a plan view of the same with the driving pulley omitted.

In the drawing like numerals of reference indicate corresponding parts in the different figures.

The device comprises two main parts a bowl shaped member and a second member concentric therewith between which is disposed a thin film of the liquid to be tested. One of these 40 parts is a rotor and the other a stator. Preferably the bowl shaped member 1 is the stator and the member 11 the rotor. By "bowl shaped" is to be understood that the interior of the stator is of such a shape that when the rotor, 45 which has a corresponding exterior shape, is moved axially relative to the stator the distance between the surfaces is varied and thus the thickness of any liquid contained between the two. In the preferred form both surfaces are 50 substantially conical. The stator is formed on

or connected with the base 2. The upper edge or rim of the stator extends laterally and terminates in the annular trough 4.

The base 2 is provided with the bearing support 6, which is formed with a bridge carrying the bearing 7. The bearing support 6 is formed with the depending annular flange 8 which fits closely within the rim 5 of the base 2 to thus position the support 6 relative to the base 2 and therefore to the stator. Lifting screws 9 are threaded through the bearing support 6 and bear upon the upper surface of the rim 5. These serve as a means for backing off the bearing support 6 in case it becomes stuck or gummed up with the liquid being tested.

In the bridge of the bearing support the bearing 7 is centrally positioned in axial alignment with the stator and through the bearing the spindle 10 extends so as to be rotatable in and 5 slide lengthwise of the bearing. To the 20 spindle is secured the rotor 11 which in its lower part is concentric with the stator and is formed with an upwardly extending rim 12 extending well above the rim of the bowl of the stator.

Set in a recess in the lower end of the rotor 25 in alignment with the axis thereof is a ball 13 forming a thrust bearing, which ball is adapted to run in a recess formed in the upper end of the block 14 which is preferably threaded into the apex of the bowl to form a bearing for the 30 ball 13. The block is thus readily renewed in case of wear. It may be also used to adjust the space left between the adjacent surfaces of the rotor and stator as may be required. Usually the ball and bearing will be so positioned relative to one another that a space of about fifteen 35 one-thousandths of an inch is left between the adjacent surfaces of the rotor and stator.

The base 2 of the stator is hollow so that it 40 forms a water jacket for the exterior of the stator. Within the hollow base is fitted the cylindrical baffle 15, from the upper rim of which depends the frusto-conical baffle 16. A water inlet 17 is provided leading into the space outside the cylindrical baffle while the outlet 18 45 communicates with the space within the cylindrical baffle. Ice water entering through the inlet 17 is thus compelled to pass in a stream over the outer surfaces of the stator, thus efficiently cooling the same.

To the upper end of the spindle 10 is secured a 50 pulley 19, around which is wrapped a cable 21 which passes over the sheave 20 carried by any suitable support and has a weight 22 secured to 55

its end. The weight thus serves to rotate the rotor 11.

The operation of the device is substantially as follows:—Cooling liquid, usually ice water, is kept 5 continually circulating through the base so that the bowl of the stator is maintained at a temperature very close to the freezing point. The rotor and bearing support are then removed from their position on the base and a quantity of the 10 hot liquid to be tested is poured into the bowl 1. The actual quantity poured in needs to be a little more than enough to fill the gap between the stator and the rotor when the latter is in position and a suitable quantity is easily estimated by eye 15 or otherwise approximately measured. The bearing support is then replaced and the rotor and spindle pushed downward through the bearing until further descent is prevented by the ball 13 taking up its position on the block 14. During 20 this descent, which occupies only a few seconds of time the fluid in the bowl is forced to form a thin film occupying the space between the rotor and stator and completely filling it, excessive fluid overflowing into the trough 4. The rotor is then 25 driven by means of the cord and weight and the time occupied by one or more revolutions measured. This time is the measure of the viscosity of the fluid. The rotor assembly and bearing support are removed, the rotor and bowl of the stator 30 wiped clean, whereupon the instrument is ready for a repetition of the operation on a new sample.

Each repetition of the operation; that is, pouring in the sample, assembling the instrument, timing the rotation, dismantling the instrument 35 and cleaning it occupies some two to three minutes.

It is found in practice that the fluid is cooled from temperatures as high as 550° F. to freezing point in the short time required to assemble the 40 instrument. The instrument is thus of special value when the progress as regard to viscosity of a heated fluid, occurring in a processing vessel, is to be followed up to a desired final state which is indicated by the attainment of a certain viscosity. This instrument thus makes it possible to 45 control the preparation of fluids, such as varnishes, which are so thin at the processing temperature that they offer little real resistance to the motion of the rotor but which have a very considerable viscosity at 32° F.

The cooling of the rotor by filling its interior with ice water may be resorted to as a supplement to the cooling of the stator.

What I claim as my invention is:

55 1. A viscosimeter comprising an imperforate bowl-shaped member having an open top; a second imperforate member concentric with and complementing the first and normally positioned within the bowl with its outer surface slightly 60 spaced from the inner surface of the bowl, the said members being axially displaceable relative to one another so that liquid placed in the bowl when the said members are separated is squeezed into a thin film between the members when the 65 latter are restored to their normal co-operative position.

2. A viscosimeter according to claim 1 in which the bowl-shaped member is formed with its upper margin below the level of the top of the other member when the two are in co-operative position to provide an overflow for surplus liquid.

3. A viscosimeter comprising an imperforate

bowl-shaped stator; a base carrying said stator; a bearing supported from the said base in axial alignment with the stator; a spindle journaled in and slideable through the bearing; an imperforate rotor concentric with the stator and secured to the spindle; and a thrust bearing between the rotor and stator defining the axial position of the rotor relative to the stator.

4. A viscosimeter comprising an imperforate bowl-shaped stator; a water jacket surrounding 10 the stator; baffles in the water jacket to direct flow over the outer surface of the stator; an imperforate rotor concentric with the stator and mounted thereon to slide axially thereof; and a thrust bearing between the rotor and stator defining the axial position of the rotor relative to the stator.

5. A viscosimeter comprising an imperforate bowl-shaped stator; an imperforate rotor concentric with the stator and mounted thereon to 20 slide axially thereof; and a thrust bearing between the rotor and stator defining the axial position of the rotor relative to the stator, the rim of the bowl being positioned below the top of the rotor when the rotor and stator are in co-operative 25 position to provide an overflow for surplus liquid.

6. A viscosimeter comprising an imperforate bowl-shaped stator; an imperforate rotor concentric with the stator and mounted thereon to 30 slide axially thereof; a thrust bearing between the rotor and stator defining the axial position of the rotor relative to the stator; the rim of the bowl being positioned below the top of the rotor when the rotor and stator are in co-operative 35 position; and an annular trough to which said rim discharges.

7. A viscosimeter comprising an imperforate bowl member having a substantially conical inside surface and an open top; a second imperforate member having a substantially conical outer surface similar to that of the inside of the bowl, the 40 said members being relatively rotatable and also axially displaceable to vary the spacing of the aforesaid surfaces; and adjustable means for setting the minimum spacing.

8. A viscosimeter according to claim 1 in which the bowl-shaped member is formed with its upper margin below the level of the top of the other member when the two are in co-operative position to provide an overflow for surplus liquid; 50 and a water jacket is formed about the exterior surface of the bowl-shaped member.

9. A viscosimeter comprising an imperforate bowl-shaped stator member; an imperforate rotor member concentric with and complementing the 55 stator member and normally positioned within the stator with its outer surface slightly spaced from the interior surface of the said stator; a base carrying the stator; a bearing supported from said base; a spindle journaled in and slideable through said bearing and to which the rotor member is secured, the said rotor member being therefore axially displaceable relative to the stator member so that liquid placed in the stator member when the members are separated is squeezed 60 into a thin film between the members when the rotor is restored to its normal co-operative position with the stator; and a thrust bearing between the rotor and stator defining the normal axial position of one relative to the other.
